(57) **CLAIM**

The ornamental design for a light, as shown and described.

DESCRIPTION

FIG. 1 is a perspective view of a light showing my new design;
 FIG. 2 is another perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof; and,
 FIG. 9 is an enlarged view of portion 9 shown in FIG. 1.
 The light is shown with a symbolic break in its length and the appearance of any portion of the light between the break lines form no part of the claimed design. The dot-dash broken lines illustrate an enlarged portion of the design and form no part of the claimed design.
